OIL BURNER

Charles E. Swallow, Worcester, Mass.

Application January 13, 1936, Serial No. 58,790

3 Claims. (Cl. 158—77)

This invention relates to oil burners and particularly to an oil burner designed for industrial low temperature work.

My invention is embodied in an oil burner of the type having a rotary nozzle, and one object of the invention is to provide an oil burner of this type which is highly efficient and in which the oil will be thoroughly atomized and mixed with the air to provide the combustible mixture.

10 In many burners having revolving nozzles a considerable vacuum is created at the end of the nozzle when the burner is in operation, and the presence of such vacuum tends to retard the flame and also tends to counteract the atomization of 15 the oil and to cause more or less oil to gather in drops at the delivery end of the nozzle. Another object of my invention is to provide improvements in burners having revolving nozzles by which the creation of such a vacuum, at the end of the revolving nozzle, and its deleterious effects is eliminated.

In carrying out my invention I employ a housing having an air inlet and a nozzle portion presenting an air outlet, and I also employ a rotary nozzle situated axially of the air outlet and forming with the nozzle portion an annular passage for the discharge of air. The rotary nozzle is provided with a portion of progressively-decreasing diameter extending through and beyond the nozzle portion of the housing and which gives the nozzle a streamline effect that prevents the formation of a vacuum at the end of the rotary element. This rotary nozzle is rotated rapidly by the air passing through the housing from the inlet to the outlet and the parts are so constructed that the air delivered from the circular air delivery opening will be given a whirling movement in one direction, while the oil is delivered outwardly into the whirling air current with a whirling motion which is opposite to that of the air. The impact of the whirling oil jets with the oppositely-whirling air results in a fine atomization of the oil and complete mixture of the oil with the air, thus producing a highly efficient 40 combustible mixture.

In order to give an understanding of the invention I have illustrated in the drawing a selected embodiment thereof which will now be described after which the novel features will be pointed out 50 in the appended claims.

In the drawing:

Fig. 1 is a sectional view of a burner embodying my invention.

Fig. 2 is a transverse sectional view of the nozzle 55 taken through the vanes 23.

Fig. 3 is a fragmentary edge view of the rotor portion of the nozzle; and

Fig. 4 is a diagrammatic view illustrating the manner in which the oil and air are mixed to produce the combustible mixture.

My improved burner comprises a housing member 1 having an air inlet opening 2 and a nozzle portion 3 provided with an air discharge opening 4. The nozzle portion 3 is shown as formed in a separate piece from the body of the housing 1 and it is detachably secured thereto through suitable bolts 5. The rotary nozzle member is indicated generally at 6 and it is provided with a body portion 7 which is rotatively mounted on a tubular extension 8 integral with the body of the 15 housing and projecting into the nozzle portion 3. Suitable ball bearings 9 are provided for rotatively supporting the nozzle member 6, there being two separate ball bearings which are spaced by the sleeve 10 that is secured to the tubular 20 extension 8 by means of a set screw 11. The inner end of the body 7 extends beyond the inner bearing 9 and a retaining ring 12 is secured within the inner end of the body 7 by means of set screws 13. This retainer ring 12 prevents outward 25 longitudinal movement of the nozzle member.

The nozzle member 6 has a portion 14 of progressively-decreasing diameter extending through and beyond the air discharge opening 4, the projecting end portion 15 of the nozzle being closed 30 and preferably being rounded as shown. The nozzle is formed with an interior oil chamber 16 into which oil is fed through a port 17 extending axially of the tubular extension 8, the supply of oil from the oil inlet 18 being controlled by the 35 usual needle valve 19.

The oil chamber 16 of the nozzle communicates through openings 20 with an annular chamber 21 having an annular discharge opening or port 22 which is situated just beyond the end of the nozzle 40 portion 3 of the housing.

Provision is made for rapidly rotating the nozzle during the operation of the burner, for which purpose said nozzle is provided with a plurality of vanes 23 which are acted on by the air traveling through the chamber 24 of the housing from the inlet 2 to the discharge opening 4.

The air delivered to the inlet 2 may be under relatively low pressure, but as the air passes through the vanes 23 it gives the nozzle a rapid 50 rotation so that the oil delivered from the annular discharge opening 22 will be thrown outwardly with a rapid whirling motion. The means for rotating the nozzle also results in giving the annular stream of air, which is delivered through 55

the annular discharge opening 4, a whirling motion in the opposite direction to that of the oil, the result being that the annular stream of oil which is whirling in one direction is thrown outwardly into an annular stream of air which is whirling in the opposite direction. The result of this is that the oil becomes very thoroughly atomized and mixed with the air, thus producing an extremely efficient combustible mixture.

10 This opposite whirling motion of the air and the oil results from the character of the vanes 23. The vanes are so constructed that the two adjacent faces 25, 26 of any two adjacent vanes are parallel with each other, as shown in Fig. 2, and 15 are inclined relatively to the axis, as shown in Fig. 3. Because of this parallel arrangement the space 27 between any two adjacent vanes 23 has the same width at the periphery of the vanes as at the base thereof so that as the moving current of air strikes the faces 25 of the vanes, as 20 shown by the arrows *a* in Fig. 3, there is no tendency for the air to flow off from the ends of the vanes but the full effect of the air pressure is transmitted to the vanes to give a rotary motion 25 to the nozzle in the direction of the arrows *c*. As the air passes out from the spaces 27 it is given a whirling motion in the direction of the arrows *b* and this whirling motion is in an opposite direction to that in which the nozzle is 30 rotating. By this means the spray of oil will be delivered outwardly from the annular space 22 into the annular sheet of air which is issuing from the air delivery opening 4 with a whirling motion in a direction opposite to that of the 35 stream of air. This is shown diagrammatically in Fig. 4 which may be considered as a view looking toward the nozzle from the right. In said Fig. 4 the circular row of arrows *b* indicates the direction of whirling motion of the air issuing 40 from the annular port 4, and the arrows *d* indicate the whirling motion of the oil issuing from the annular discharge opening 22. Because of the rotative movement of the nozzle the oil is thrown outwardly in approximately a tangential 45 direction and will thus be directed against the oppositely-whirling sheet of air illustrated by the arrows *b* in Fig. 4.

The progressively-tapered shape of the portion 6 of the nozzle together with the fact that 50 it projects beyond the nozzle portion 3 of the housing gives to the nozzle a streamline effect which permits the air and oil mixture to flow off from the end of the nozzle without creating any vacuum at said end, the presence of which has a 55 detrimental effect on the operation of the burner.

I claim:

1. An oil burner comprising a housing having an air inlet and a nozzle portion provided with a discharge opening, a rotary nozzle member situated axially of said discharge opening and forming with the wall thereof an annular air delivery passage, said nozzle member having an interior chamber and a closed end projecting beyond the nozzle portion of the housing, vanes 65 extending radially from the nozzle member and having inclined faces whereby the impact of the air passing through the housing against the

vanes causes the nozzle member to rotate and produces a whirling motion in the air passing through the annular air delivery passage, and means for delivering oil to said interior chamber, said nozzle member being provided with an annular oil chamber open at one end on the exterior thereof at a point just beyond the nozzle portion of the housing, said nozzle member also being provided with communicating passages between said annular chamber and the interior chamber. 10

2. An oil burner comprising a housing having an air inlet and a nozzle portion provided with a discharge opening, a rotary nozzle member situated axially of said discharge opening and forming with the wall thereof an annular air delivery passage, said nozzle member having an interior chamber and a closed end projecting beyond the nozzle portion of the housing, vanes 15 extending radially from the nozzle member with the adjacent faces of any two adjacent vanes 20 parallel to each other and inclined to the direction of air flow, whereby the impact of the air passing through the housing against the vanes causes the nozzle to rotate and produces a whirling motion in the air passing through the annular air delivery passage, and means to deliver oil to said interior chamber, said nozzle member having an annular oil chamber opening at one end on the exterior thereof and also having communicating 25 passages between said annular chamber and the interior chamber, the rotary motion of the nozzle member delivering the oil from the open end of the annular oil chamber outwardly into the whirling stream of air and with a whirling motion opposite to that of the 30 stream of air.

3. An oil burner comprising a housing having an air inlet and a nozzle portion provided with a discharge opening, a rotary nozzle member situated axially of said discharge opening and forming with the wall thereof an annular air delivery passage, said nozzle member having an interior chamber and a closed outer end which projects through and beyond the nozzle portion 40 of the housing, the portion of the nozzle member 45 which thus projects through and beyond the housing having a progressively decreasing diameter in a direction toward said closed end, vanes extending radially from the nozzle member and having inclined faces whereby the impact of the air passing through the housing against the vanes causes the nozzle to rotate and produces a whirling motion of the air passing 50 through the annular air delivery passage, and means to deliver oil to said interior chamber of the nozzle member, said nozzle member having on its exterior an annular discharge port and also having passages which form a communication between said port and said interior chamber and through which oil flows from said chamber to 55 said discharge port, the rotary motion of the nozzle member delivering the oil from said annular discharge port outwardly into the whirling stream of air and with a whirling motion opposite to that of the stream of air. 65
